UNITED STATES PATENT OFFICE.

WALTER I. KIRK, OF CHICAGO, ILLINOIS, ASSIGNOR TO LYON & HEALY, OF CHICAGO, ILLINOIS, A CORPORATION OF ILLINOIS.

HARP.

1,134,207.

Specification of Letters Patent.

Patented Apr. 6, 1915.

Application filed October 9, 1911. Serial No. 653,652.

To all whom it may concern:

Be it known that I, WALTER I. KIRK, a citizen of the United States of America, and resident of Chicago, Illinois, have invented 5 a certain new and useful Improvement in Harps, of which the following is a specification.

My invention relates to stringed instruments, such as harps, harp guitars or any 10 stringed instrument in which sharping fingers are used, and relates more particularly to an improved construction of such sharping fingers, and to the means for operating the same.

15 My invention is especially designed for use in connection with a single-action harp, and an object is to simplify the mechanism required for operating the sharping fingers, thereby greatly reducing the cost of the 20 harp.

A further object is to provide an automatic locking means controlled by the tension of the string, for holding the sharping finger in operated position. Heretofore it 25 has been customary to operate these sharping fingers by means of pedals. This arrangement, however, necessitated a complicated chain of mechanism in the column and neck of the harp, and thus greatly increased the cost of the same.

30 By my improved arrangement I have provided a much simpler operating mechanism for the sharping fingers, which mechanism is located on the neck of the instrument 35 within easy reach of the harpist.

These and other objects of my invention will be more readily understood by having 40 reference to the accompanying drawings, in which similar reference characters refer to similar parts, and in which—

Figure 1 is a side elevation of a portion of a harp embodying my invention. Fig. 2 is a similar view with the front action plate removed and showing but a single train of 45 links in order to simplify the drawing. Fig. 3 is a sectional detail. Fig. 4 is a sectional view taken on line 4—4 of Fig. 3. Fig. 5 is an enlarged detail showing the manner in which the sharping finger is locked in operated position. Fig. 6 is a side elevation of 50 a portion of a harp showing a modified form of my invention. Figs. 7 and 8 are enlarged details of this modified form. Fig. 9 is a sectional detail of a sharping finger

showing the various parts in detached relationship.

As shown in Figs. 1 and 2, 11 represents the upper portion of the column of the harp to which is connected the neck 12 in the usual manner. This neck portion carries 60 the front and back action-plates 13 and 14. The strings 15 are secured to the tuning pins on the neck 12 in the usual manner. Mounted adjacent to each of the strings and a short distance below the tuning pins, there is a sharping finger 16 by means of which the pitch of the corresponding string can be raised a half tone. Corresponding sharping fingers in each octave are connected together by a series of links 70 as shown in Fig. 1, whereby the corresponding string of each octave may be raised a half tone by a single operation. Each of these sharping fingers 16 is carried by a disk 17 mounted upon a spindle 18, as shown 75 in Fig. 3. This spindle is provided with a cone-shaped bearing 19 fitting within a bearing opening in the front action plate 13, while the opposite end of the spindle is provided with a reduced portion adapted 80 to fit within a hollow cap 20 which is in threaded engagement with an opening in the back action plate 14. The interior of this hollow cap is provided with a small spiral spring, which is adapted to bear against 85 the end of the spindle 18, thereby holding the cone bearing 19 firmly within the cone-shaped opening in the front action plate, thus preventing the sharping finger from rattling or working loose. The construction 90 of this cap and spring is clearly shown in the upper part of Fig. 3, in connection with the spindle 21, which is similar in construction to the spindle 18. The corresponding spindles 18 of each octave are 95 connected together by means of a train of links 22 and arms 23, as clearly shown in Fig. 1. Mounted upon one of the spindles 18 there is a pivoted arm 24 to the opposite end of which is connected the link 25 which 100 is connected to the arm 26 mounted upon the spindle 21. This spindle is mounted in the front and back action plates in a manner similar to the spindle 18, and carries the operating handle 27. A split collar 28 105 is clamped upon the spindle 21, and is provided with a pair of lugs 29 and 30 which engage with the pin 31 mounted upon the

front action plate to limit the movement of the operating handle 27.

By the above construction it will readily be seen that by moving the operating handle 27 in the arc of a circle this motion is transmitted through the connecting links to each of the corresponding spindles 18, thereby operating the associated sharping finger, one in each octave.

10 As stated above, the movement of the operating lever is limited by means of the stop lugs 29 and 30. The lug 29 is so positioned that when it strikes the pin 31 the sharping finger has been revolved from the position shown in dotted lines to the position shown in full lines in Fig. 5, so as to bear against the string 15, forcing the same slightly out of alinement, and has reached a position below the center line of the disk 17. In this position the sharping finger 16 is securely locked in place, as movement in one direction is prevented by means of the lug 29, while movement in the opposite direction is prevented by means of the tension of the string 15. This tension upon the string exerts a force on the pin 16 acting toward the right (looking at Fig. 5), and in order for the finger 16 to rotate back to its normal position it would be necessary for it to move slightly to the left, owing to the fact that it has revolved below the center line of the disk 17. It will thus be seen that I have devised a very simple and efficient means whereby the tension upon the string serves to automatically hold the sharping finger in position.

15 I have described the operating mechanism for a single series of sharping fingers, one for each octave, and, of course, it will be understood that I provide a similar chain of mechanism for each string of the octave. The corresponding operating handles 27 are preferably grouped together upon the neck of the instrument within easy reach of the harpist. These operating handles are marked to designate the strings which they control, and are grouped in a series corresponding to the usual sequence of the pedals of a pedal harp. That is, the operating 20 handles referring to the strings they control would be arranged in the order of D, C, B, E, F, G, A. This is purely for convenience, so that when one has learned the pedal series he can more readily learn to operate the levers.

25 In Figs. 6 to 9, I have shown a slightly modified form of my invention which is adapted for use with a single plate harp; that is, a harp of smaller size having but a single action plate. In this modification I omit all connecting links, it being necessary to operate each sharping finger individually. This makes the arrangement very simple, so that the sharping fingers can be applied to 30 the small inexpensive harps.

The sharping finger 16^a and method of mounting the same is shown in detail, and is somewhat similar to the construction heretofore described. The sharping finger 16^a is carried by the disk 17^a, which disk is 35 mounted on a second disk 17^b on the spindle 18^a. This spindle is provided with a cone bearing 19^a which fits within a cone-shaped recess in the action plate. It will be noticed that this cone bearing is beveled in the opposite direction from that shown in Figs. 1 to 5, on account of the fact that it is mounted on the outside of the action plate instead of the inside. The spindle 18^a passes through the neck 12 on the cylindrical opening in the 40 neck, which opening is enlarged at 32. A washer 33 surrounds the spindle 18^a and rests in the lower portion of the enlarged opening. The sleeve 34 and spring 35 fit over the spindle 18^a and are held in place by means of the cap 36 and set-screw 37. The set-screw 37 engages with the inside of the spindle 18^a, thus locking the cap and spindle together, and the spring 35 presses outward upon the cap 36, thus holding the cone bearing 19^a firmly in place and preventing the spindle from rattling or working loose. The disk 17^b is provided with a lug 38 which engages with the arc-shaped slot 39 in the action plate 13^a. The sharping fingers 16^a bear against the strings and in order to operate them it is merely necessary to press against the finger and rotate the same until the lug 38 reaches the end of the slot 39, in which position the sharping finger has 45 reached a position below the center line of the disk 17^a, whereby it is automatically held in position by the tension of the string, in the manner described.

50 It will thus be seen that I have devised a very simple and effective sharping finger, which is automatically held in operated position.

55 While I have shown certain embodiments of my invention, it will be understood that I do not limit myself to the exact construction shown, but that various changes will suggest themselves to anyone skilled in the art.

60 Furthermore, while I have illustrated my invention in connection with a harp, it will be readily understood that the sharping fingers may be employed in connection with any form of stringed instrument in which sharping fingers are employed.

65 What I claim as my invention is:

1. In a musical instrument, a tuned string, a sharping finger for raising the pitch of said string, and means for limiting the rotation of said finger, said finger being so positioned with respect to said string that the tension of the string holds said finger in operated position.

2. In a musical instrument, a tuned string, a sharping finger for raising the pitch of

- said string, a disk upon which said finger is eccentrically mounted, means for rotating said disk to cause said finger to bear against said string, means for stopping said finger 5 at a point past the center line of said disk which passes through the point of contact between said string and disk, whereby the tension of the string automatically holds said finger in operated position.
- 10 3. In a musical instrument, a tuned string, a sharping finger for raising the pitch of said string, a disk upon which said finger is eccentrically mounted, means for rotating said disk to cause said finger to bear against said string, and means engaging said disk for preventing said disk and finger from being rotated beyond a point which is past the center line of said disk which passes through the point of contact of said string 20 and disk, whereby the tension of the string automatically holds said finger in operative position.
4. In a harp, a column, a neck secured thereto, a plurality of tuned strings secured to said neck, a sharping finger adjacent each string for raising the pitch of that string, means for limiting the rotation of said fingers, said fingers being so positioned with respect to their respective strings that the
- 15 tension of the strings holds their respective fingers in operative position, and operating handles mounted upon said neck for operating said sharping fingers.
5. In a harp, a column, a neck secured thereto, a plurality of tuned strings secured to said neck, a sharping finger located adjacent to each string for raising the pitch of said strings, a disk upon which each finger is eccentrically mounted, means for rotating said disks to cause said fingers to bear 40 against their respective strings, means for engaging said disks for preventing said disks and fingers from being rotated beyond a point which is past the center line of said disks which passes through the point 45 of contact of said strings and their respective disks, whereby the tension of said strings operatively holds said fingers in operative position, and operating handles mounted upon said neck for operating said 50 sharping fingers.

Signed by me at Chicago, Illinois, this 19th day of Sept., 1911.

WALTER I. KIRK.
